LAWRENCE C. LONGSTREET, OF DUNELLEN, NEW JERSEY, ASSIGNOR OF ONE-THIRD TO
GEORGE VOEHL, OF DUNELLEN, NEW JERSEY

BOAT PROPULSION MECHANISM

Application filed March 6, 1930. Serial No. 433,638.

This invention relates to new and useful improvements in boat propulsion mechanism and has for its primary object to provide, in a manner as hereinafter set forth, a mechanism of this character embodying a construction and arrangement whereby a material increase in speed will be attained with a given expenditure of engine power.

Another important object of the invention is to provide, in a manner as hereinafter set forth, a boat propulsion mechanism which may be expeditiously mounted in operative position on the stern portion of the boat in such a manner that a drive shaft from the engine is disposed above the water line.

Another important object of the invention is to provide boat propelling means embodying a construction and arrangement whereby a propeller will be permitted to remain stationary while the engine is running.

A further important object of the invention is to provide a boat propulsion mechanism which is adapted to be expeditiously mounted on various types of conventional boats which are already in use and this without the necessity of materially altering the same.

Other objects of the invention are to provide, in a manner as hereinafter set forth, a boat propulsion mechanism of the character set forth which will be simple in construction, strong, durable, efficient in its use and which may be manufactured at low cost.

All of the foregoing and still further objects and advantages of the invention may become apparent from a study of the following specification taken in connection with the accompanying drawings wherein like characters of reference designate corresponding parts throughout the several views, and wherein:—

Figure 1 is a view in side elevation showing a boat propulsion mechanism mounted in operative position on the rear end of a boat, the stern portion of said boat being shown in vertical longitudinal section.

Figure 2 is a fragmentary detail view broken away in vertical section and illustrating the means whereby a propeller is opera-

tively connected to or disconnected from the engine.

Figure 3 is a vertical sectional view through the gearing mechanism.

Figure 4 is a horizontal sectional view taken substantially on the line 4—4 of Figure 3 looking downwardly in the direction indicated by the arrows.

Referring to the drawings in detail, the reference character 1 designates the stern portion of a boat having a rudder 2 mounted for swinging movement on the rear end thereof in the usual manner and 3 designates the engine or power plant of the boat.

A vertically disposed elongated tubular shaft housing 4 is mounted on the rear end of the boat in spaced relation thereto through the medium of the supporting bracket 5 and said shaft housing has formed integrally on its upper and lower ends enlarged half sections 6 and 7, respectively. A complementary half section 8 is detachably secured on the half section 6 and said sections 6 and 8 constitute a gear housing.

A complementary half section 9 is detachably secured to the lower half section 7 in a manner to form a gear housing on the lower end of the shaft housing 4.

A vertically disposed shaft 10 extends longitudinally through the housing 4 and through the lower gear housing formed by the sections 7 and 9 and the lower end of said shaft is mounted for rotation in a socket 11 provided therefor in the section 9. The upper end of the shaft 10 terminates within the gear housing formed by the sections 6 and 8. Said upper end being spaced from the section 8.

The upper gear housing is provided with a forwardly disposed extension 12 which is connected to a tubular housing 13 which extends to the engine 3. An engine drive shaft 14 is operatively connected to the engine 3 and extends therefrom through the shaft housing 13 into the upper gear housing formed by the complementary sections 6 and 8 through the extensions 12 thereof and said shaft is journaled in the roller bearing 15 in the extension 12. A thrust bearing 16 is also provided in the extension 12. A pinion gear 17 is fixed

on the inner end of the engine propeller shaft 14 and said pinion gear is constantly in mesh with a ring gear 18 mounted for rotation in the upper gear housing and having formed integrally thereon the gear casing 19. Planetary gears 20 are mounted for rotation within the casing 19 on the vertical walls thereof. The planetary gears 20 are constantly in mesh with a beveled gear 21 having an integral sleeve 22 depending therefrom and mounted on the upper end portion of the shaft 10. The sleeve 22 extends through the ring gear 18 and into the upper end portion of the shaft housing 4 and roller bearings 23 are disposed between the said sleeve and the shaft housing. It will further be seen that the sleeve 22 constitutes means for rotatably retaining the ring gear 18 in position in the upper gear housing. A beveled gear 24 is disposed above the planetary gears 20 and is constantly in mesh therewith and said gear 24 is provided with an integral sleeve 25 which extends rotatably through the upper wall of the casing 19 and has fixed therein a comparatively short shaft 26 having a transverse socket 27 in its upper end portion, said upper end portion projecting above the sleeve 25 and disposed rotatably in a socket provided therefor in the upper half section 8, as clearly illustrated in Figure 2 of the drawings. A roller bearing 28 is disposed between the upwardly projecting end portion of the sleeve 25 and the adjacent walls of the half section 8 in which said sleeve 25 rotates. The socket 27 is adapted to be brought into registry with a horizontally disposed opening provided in the upper end portion of the half section 8. A locking pin 29 extends slidably through the opening in the half section 8 and is adapted to have its inner end portion inserted in the socket 27 in a manner to lock the shaft 26 and the gears 24 which is fixed thereon against rotation. The outer end of the pin 29 is provided with a right angularly disposed handle portion 30 and a coil spring 31 is connected to the pin 29 and the half section 8 in a manner to yieldingly urge said pin 29 into engagement with the shaft 26. A beveled gear 32 is fixed on the lower end portion of the shaft 10 within the lower gear housing formed by the half sections 7 and 9 and said gear 32 is provided with an integral sleeve 33 extending upwardly on the shaft 10 into the lower end of the housing 4. A roller bearing 34 is provided between the sleeve 33 and the housing 4. The lower gear housing is provided with a rearwardly disposed extension 35 having an annulus 36 removably secured on the free end thereof and constituting means for retaining the roller bearing 37 in the extension 35. A propeller shaft 38 extends into the lower gear housing through the extension 35 and is supported for rotation through the medium of

the roller bearing 37. A pinion gear 39 is fixed on the inner end portion of the propeller shaft 38 and is constantly in mesh with the gear 32 for actuation thereby. A thrust bearing 40 is also disposed in the inner end portion of the extension 35. A propeller 41 is fixed on the rear end portion of the shaft 38.

As illustrated to advantage in Figures 1 and 3 of the drawings, the lower half section 9 of the lower gear housing is provided with an integral downwardly and rearwardly curved fin 42 which constitutes a guard for the propeller 41. The intermediate portion of the shaft housing 4 is preferably of the cross sectional configuration illustrated in Figure 4 of the drawings for the purpose of reducing resistance to the water when the boat is moving therethrough.

In use, when the engine 3 is running and it is desired to drive the propeller 41, the pin 29 is inserted in the socket 27 in a manner to hold the shaft 26 and the beveled gear 24 against rotation. The drive shaft 14 from the engine then rotates the ring gear 18 through the pinion gear 17 and the planetary gear 20 travel around the gear 24 and impart rotary movement to the gear 21 by this operation, as will be understood. The shaft 10 is thus rotated and the propeller shaft 38 is actuated through the medium of the gears 32 and 39 as will be obvious. It is understood, of course, that any desired ratio of the various gears may be provided.

Should it be desired to render the propeller 41 inoperative even though the engine 3 is running, this may be expeditiously accomplished by simply withdrawing the pin 29 from the socket 27 and the gear 24 which is mounted on the shaft 26 will thus be free to rotate and the planetary gear will now travel around the gear 21, and permits same to remain stationary.

It is believed that the many advantages of a boat propulsion mechanism constructed in accordance with this invention will be readily understood, and although the preferred embodiment of the invention is as illustrated and described, it is to be understood that changes in the details of construction may be had which will fall within the scope of the invention as claimed.

What is claimed is:—

1. In a boat propulsion mechanism of the character described, a gear housing, a driving shaft extending into the gear housing, a gear fixed on the driven shaft and disposed within the housing, a gear mounted for rotation in the housing and disposed in spaced opposed relation to the first named gear, said driving shaft extending rotatably into the housing and having a pinion gear fixed on its inner end, a ring gear mounted for rotation in the housing in mesh with the pinion gear for actuation thereby, planetary gears rotatably mounted on the ring gear and in mesh
